(57) CLAIM

The ornamental design for a handle for liquid and lotion applicators, as shown and described.

DESCRIPTION

FIG. 1 is a top perspective view of the first embodiment of a handle for liquid and lotion applicators showing my new design;

FIG. 2 is a top plan view of the first embodiment;

FIG. 3 is a front view thereof, the other being a mirror image.;

FIG. 4 is a top perspective view of a second embodiment of a handle for liquid and lotion applicators;

FIG. 5 is a side view of both embodiments;

FIG. 6 is a bottom view of both embodiments;

FIG. 7 is a top plan view of the embodiment shown in FIG. 4;

FIG. 8 is the other side view of both embodiments; and,

FIG. 9 is a rear view of the embodiment shown in FIG. 4.
